CLAIM

The ornamental design for a wearable chain, as shown and described.

DESCRIPTION

FIG. 1 is a top plan view of a wearable chain and including an enlarged partial top view showing ten links;

FIG. 2 is an enlarged detail view of a portion of the wearable chain shown in FIG. 1;

FIG. 3 is a detailed perspective view of the wearable chain in FIG. 1 shown in an alternate configuration;

FIG. 4 is a top plan view thereof;

FIG. 5 is a bottom plan view thereof;

FIG. 6 is a front elevational view thereof;

FIG. 7 is a rear elevational view thereof;

FIG. 8 is a right side elevational view thereof;

FIG. 9 is a left side elevational view thereof;

FIG. 10 is a top plan view of a wearable chain and including an enlarged partial top view of a second embodiment showing twelve links;

FIG. 11 is an enlarged detail view of a second embodiment of a portion of the wearable chain shown in FIG. 10;

FIG. 12 is a detailed perspective view of a second embodiment of the wearable chain in FIG. 10 shown in an alternate configuration;

FIG. 13 is a top plan view of a second embodiment thereof;

FIG. 14 is a bottom plan view of a second embodiment thereof;

FIG. 15 is a front elevational view of a second embodiment thereof;

FIG. 16 is a rear elevational view of a second embodiment thereof;

FIG. 17 is a right side elevational view of a second embodiment thereof;

FIG. 18 is a left side elevational view of a second embodiment thereof;

FIG. 19 is a top plan view of a wearable chain and including an enlarged partial top view of a third embodiment showing sixteen links;

FIG. 20 is an enlarged detail view of a third embodiment of a portion of the wearable chain shown in FIG. 19;

FIG. 21 is a detailed perspective view of a third embodiment of the wearable chain in FIG. 19 shown in an alternate configuration;

FIG. 22 is a top plan view of a third embodiment thereof;

FIG. 23 is a bottom plan view of a third embodiment thereof;

FIG. 24 is a front elevational view of a third embodiment thereof;

FIG. 25 is a rear elevational view of a third embodiment thereof;

(Continued)

FIG. 26 is a right side elevational view of a third embodiment thereof;
 FIG. 27 is a left side elevational view of a third embodiment thereof;
 FIG. 28 is a top plan view of a wearable chain and including an enlarged partial top view of a fourth embodiment showing twenty links;
 FIG. 29 is an enlarged detail view of a fourth embodiment of a portion of the wearable chain shown in FIG. 28;
 FIG. 30 is a detailed perspective view of a fourth embodiment of the wearable chain in FIG. 28 shown in an alternate configuration;
 FIG. 31 is a top plan view of a fourth embodiment thereof;
 FIG. 32 is a bottom plan view of a fourth embodiment thereof;
 FIG. 33 is a front elevational view of a fourth embodiment thereof;
 FIG. 34 is a rear elevational view of a fourth embodiment thereof;
 FIG. 35 is a right side elevational view of a fourth embodiment thereof; and,
 FIG. 36 is a left side elevational view of a fourth embodiment thereof.
 The broken lines shown in the drawing views represent portions of the wearable chain which form no part of the claimed design.
